UNITED STATES PATENT OFFICE.

WILLIAM T. TYLER, OF WARSAW, VIRGINIA.

PEN CLEANER AND HOLDER.

1,089,992.

Specification of Letters Patent. Patented Mar. 10, 1914.

Application filed January 10, 1913. Serial No. 741,263.

To all whom it may concern:

Be it known that I, WILLIAM T. TYLER, a citizen of the United States, residing at Warsaw, in the county of Richmond and State of Virginia, have invented new and useful Improvements in Pen Cleaners and Holders, of which the following is a specification.

This invention relates to a pen holding device, the primary object thereof being to provide a body, which is adapted to serve as a paper weight, and a nib-receiving element carried thereby of soft material, preferably pith, into which the nibs of the pen may be inserted at any angle and which will effectively retain the same in the inserted position until withdrawn for use.

A further object is the provision of a device of this character wherein the body is provided with a recess for the reception of the nib-receiving element specified and means for removably securing the said element in position within the recess, so that the said nib-receiving element may be replaced when it is no longer fit for use.

A still further object of the invention is to provide a nib-receiving element composed of companion sections, which may be individually replaced as the occasion may demand.

The invention consists in the features of construction, combination and arrangement of parts, hereinafter fully described and claimed, reference being had to the accompanying drawing, in which:

Figure 1 is a perspective view of the device in use; Fig. 2 is a side elevation showing the securing plate in open position; and, Fig. 3 is a detail perspective view of one of the nib-receiving element sections.

In the drawing, the numeral 1 designates the body of the device, which may be constructed of wood, metal, or even glass so as to provide an object adapted to serve as a paper weight. This body is provided with a transverse recess 2 in its upper face for the reception of the nib-receiving element which has its end walls concaved as at 3. In order to reduce the cost of manufacture, especially in the construction of the body of wood or metal, this recess 2 is extended through the body so as to open through the opposite sides thereof, and a side plate 4 is secured in suitable manner to one side of the body 1 so as to form a side wall for the recess 2, this plate being provided with an

opening 5 communicating centrally with the recess 2 for a purpose which will be presently described.

The nib-receiving element for the pens is preferably in the form of a composite block 6 of vegetable matter, such as pith contained in corn stalks, or like plants, and includes a plurality of sections 7. These sections 7 may be cut so that the block will completely fill the recess 2, the ends of the block sections being convex as at 8, in order to prevent the same from becoming detached from the body 1 by vertical movement. This nib-receiving element is adapted to effectively retain the nibs of the pens in their inserted position, no matter what the angle of insertion may be, and it is capable of cleaning the pen nib and absorbing any ink that remains thereon after use. These notable characteristics of pith render the said element a decided improvement over the present-day pen holding devices constructed of layers of paper, between which layers the pen nibs may be inserted, it being necessary to insert the pen in a plane parallel to the planes of the said layers.

Corn pith, that is the pith obtained from the stalk of the plant, does not have a very pronounced grain, and yet has a great number of substantially parallel fibers extending therethrough, which are comparatively tough and serve as effective means for reinforcing the pith and resisting lateral strain in particular. In accordance with my invention, a block of corn pith is positioned within the elongated recess in a suitable holding body so that its reinforcing fibers extend longitudinally therein. The most blunt pen nib that may be inserted into the pith block will easily penetrate the same without compressing the pith to such an extent that the pen will not be held securely in applied position. The pen nib may distort the said fibers or may sever a number of the same without destroying that shape-retaining quality of the material which renders the same peculiarly adapted for use in this capacity.

I propose to manufacture a supporting body for a corn pith nib-receiving element, which is intended for permanent use and to produce removable nib-receiving elements of the character set forth in such quantities that a new element may be readily obtainable when it is desired to replace a damaged element. In carrying out this idea, I have

constructed each nib-receiving element and the supporting body therefor in such a manner that the said element may be positioned properly within the body without the exercise of extreme care in the operation. It should therefore be apparent that an unskilled person can renew a worn out nib-receiving element without being especially familiar with the physical properties of corn pith and the exact manner in which a nib-receiving element of this material should be arranged for use in a pen holder. As the supporting body is provided with an elongated recess, and each nib-receiving element is cut of the same shape and size as the recess, so that the reinforcing fibers extend longitudinally in the element, there is only one way to position the element within the supporting body, and that is the correct way.

A securing plate 9 is pivoted adjacent one end of the side face 10 of the body 1 opposite the plate 4 by means of a removable pivot pin 11, this plate 9 being adapted to swing in a vertical plane, so that it may be swung into open position, as shown in Fig. 2, to permit withdrawal of the nib-receiving element, or may be swung downwardly into closed position, wherein it completely closes the adjacent end of the recess 2. A limiting screw-member 12 provided with a head 13 is adjustably mounted in the body 1 opposite the pivot pin 11 so as to serve as means for engagement with the lower edge of the securing plate 9 to retain the same in its closed position.

When it is desired to replace the nib-receiving element, or certain unserviceable sections thereof, a pen holder or pencil may be inserted in the opening 5, after the plate 9 is swung into open position, to force the said element laterally through the open end of the recess.

From the foregoing description it will be evident that I have provided a pen holding device of small and compact construction,

which is adapted to serve its purpose efficiently and continuously, and which may be used as a paper weight.

What is claimed is:

1. A pen holder comprising a supporting body having a recess therein opening through its upper face and one of its side faces and provided with concave end walls, the said body being provided with an opening in its opposite side communicating medially with the said recess, and a nib-receiving element positioned within the recess and consisting of a plurality of transversely alined sections having convex ends engaged with the concave end faces of the recess. 60

2. A pen holder comprising a supporting body having a recess therein opening through its upper face and one of its side faces and provided with concave end walls, the said body being provided with an opening in its opposite side communicating medially with the said recess, a nib-receiving element positioned within the recess and consisting of a plurality of transversely alined sections having convex ends engaged with the concave end faces of the recess, the said sections being adapted for lateral sliding movement within the recess during independent application or removal thereof, and a vertically swinging closure plate pivoted to the body and adapted to be moved into position wherein it will close the adjacent side of the recess. 70

3. A pen holder comprising a supporting body having an elongated recess therein, and an elongated nib-receiving element constructed of corn pith with its grain extending longitudinally, the said element being adapted to be fitted within the said recess. 80

In testimony whereof I affix my signature 85 in presence of two witnesses.

WILLIAM T. TYLER.
